UNITED STATES PATENT OFFICE.

HENRY WILHELM, OF BROOKLYN, NEW YORK.

SECTIONAL-BOX MECHANISM.

Application filed August 15, 1924. Serial No. 732,163.

This invention relates to sectional box mechanism, an object of the invention being to provide an improved construction for sectional boxes or compartments wherein a series of compartments or boxes such as letter boxes may be individually and independently locked and unlocked or opened and wherein by means of a master lock all of the boxes or compartments may be simultaneously opened.

A further object of the present invention is to provide an improved construction for sectional boxes wherein the doors of a predetermined series of boxes may be independently locked and unlocked or opened, and wherein by operating a master lock all of the boxes may be bodily swung on a main hinge or pivotal axis to permit access to the several boxes collectively.

A further object is to provide an improved construction for sectional boxes which will be more economical to manufacture, simpler in construction and which at the same time will be strong and durable. Furthermore, the construction is such that the boxes may be easily assembled and taken apart, thereby eliminating the necessity of having skilled and experienced or specially trained workmen to install the boxes, as for instance when they are installed in apartment or tenement houses.

Other objects of this invention will appear in the following description and appended claims, reference being had to the accompanying drawings forming a part of this specification wherein like reference characters designate corresponding parts in the several views and wherein Fig. 1 is a front elevation illustrating an embodiment of my invention; Fig. 2 is a vertical section taken substantially on line 2-2 of Fig. 1; Fig. 3 is a top plan view of the construction shown in Fig. 1; Fig. 4 is a view similar to Fig. 2 illustrating the boxes when swung into open position and Fig. 5 is a perspective view of the adjustable stop member for the boxes.

Before explaining in detail the present improvement and mode of operation thereof, I desire to have it understood that the invention is not limited to the details of construction and arrangement of parts which are illustrated in the accompanying drawings, since the invention is capable of other

embodiments, and that the phraseology which I employ is for the purpose of description and not of limitation.

In the present instance by way of illustration, the sectional box construction is shown as comprising two boxes adapted to be individually opened, and also collectively opened by means of a single master lock, but it will be understood that the invention is not limited to any particular number of boxes, as a larger number may be utilized where desired, the present construction being illustrative of a way in which my invention is applied. Each sectional box or compartment, two being shown by way of example in the drawings, is housed within a main box or supporting means 9. This box 9 is rectangular in shape and of suitable length to house within the ends thereof the several boxes of the section. The box 9 is set into the wall of the building and the back wall of the box is secured at the bottom and top thereof at 10 to the usual cross beams 11 of the wall. Obviously, however, the screws 10 could pass through the side walls instead of the back wall of the box 9 if this should be desired. The box 9 is thus stationary and located in fixed position and is of suitable depth in accordance with the desired depth of the several letter boxes or compartments, the top wall 12 of the main box 9 extending forwardly and terminating at its front edge in a downwardly extending flange or lip 13. The bottom of the main box 9 also extends forwardly the same distance as the top, and at its front edge a hinge plate 15 is secured thereto as by means of rivets 16. This plate 15 extends along the front inner edge of the bottom of the main box 15 the entire length thereof and at its outer edge the plate 15 is bent or partially coiled to form an open hinge member 16. It will be noted that the box 9 is entirely open at its front end.

Located or housed within the stationary box or housing 9 are a series of compartments or boxes, in the present instance shown as letter boxes, two such boxes 17 and 17^a being herein shown for the purpose of illustration. The boxes 17 and 17^a have a common back wall 18 and a common base or bottom wall 19, each extending the length of the section. The front edge of the base 19 for the several boxes is bent downwardly

2

to form a flange 20 and secured to this flange is a vertically extending apron or front wall 21 which also extends the length of the sectional boxes. The lower edge of the apron 21 and of the flange 20 are adapted to be inserted within the open hinge member 16 whereby the boxes will have a common hinge along the entire lower edge thereof through the medium of the hinge 16. From the foregoing it will be seen that since the several boxes 17 and 17^a have a common back wall 18, a common base 19 and front skirt or wall 21, the boxes will swing as a unit about the axis formed by the hinge 16. It will be obvious, however, that if preferred the boxes could be made separately and connected in any suitable manner so as to swing together. In the present instance the front wall 21 extending the length of the sectional boxes 20 preferably has a height somewhat less than the height of the boxes, and adjacent to the upper edge is provided with an outwardly pressed rib 22 and terminates in a flange 23 which is inwardly offset from the main portion of the wall 21.

The box or compartment 17 is provided with a hinged door 25 and in like manner the box 17^a is provided with a hinged door 25^a. The door 25 is hinged to the front edge of the side wall 24 of compartment 17 by means of a suitable hinge 26, and the door 25^a is hinged to the front edge of the side wall 24 of compartment 17^a by means of a suitable hinge 26^a.

Between the doors 25 and 25^a the apron 21 is provided with an upwardly extending plate or section 27 which extends to the top of the sectional boxes. This plate 27 is secured to the rear wall 18 by means of transverse members 33 and 34.

Secured to the inner upper face of the central plate 27 is a suitable spring lock 35 having a lock bolt 37. By inserting a key in the slot 36 of the lock, the bolt 37 may be shifted so as to engage behind the flange 13 of the stationary box or housing 9 or be disengaged therefrom. The lock 35 thus performs the function of a master lock, since when the lock bolt 37 is shifted downwardly 45 out of engagement with the flange 13, all of the compartments or boxes are free to swing forwardly upon the hinge 16. Each of the doors 25 and 25^a of the individual compartments 17 and 17^a is provided with a spring lock 28 having a lock bolt 30, and by inserting the key in the key slot 29, the bolt 30 may be shifted into and out of a suitable slot formed in the side wall 31 of compartment 17 or 17^a. In this manner these compartments may be independently and individually opened and locked.

It will be noted that when the master lock 35 is operated to release the lock bolt 37 from behind the flange or lip 13, the entire section of boxes as a unit will swing for-

wardly upon the hinge 16. This forward swinging movement is limited by suitable means shown in one form as an adjustable stop member 38 which may comprise a bar secured at the top edge of the rear wall 18 and extending the length thereof. This bar 38 is provided with a pair of threaded holes 39 and is secured to the back wall 18 by means of set screws 40 extending through vertical slots 41 in wall 18. By loosening the set screws 40, the bar 38 may be shifted to the position shown in Fig. 2 so as to project above the upper edge of the back wall 18. The bar 38 will be held in this position by tightening the screws 40, so that when the sectional boxes are swung forwardly on the hinge 16 as shown in Fig. 4, the stop bar 38 will engage the flange 13 thus permitting the boxes 17 and 17^a to be opened only to an extent corresponding to the depth of these boxes. The sectional boxes may be removed as a unit merely by loosening the set screws 40 and sliding them downwardly in the vertical slots 41 thus shifting the bar 38 so that the upper edge thereof will not project above the upper edge of wall 18. Upon swinging the boxes forwardly the bar 38 will clear the flange 13 thereby permitting the sectional boxes to be lifted off from the hinge 16 and thus removed, and at which time access to the screws 10, for securing the casing 9 in its opening is possible, and at other times these screws 10 are inaccessible either when the boxes are in their normally opened or closed position. It will be observed that this shifting of the bar or latch 38 permits the boxes to be shifted forward beyond their mail-receiving position at which time they may be removed, instead of which, however, the boxes may be swung further downward out of the way, thereby permitting access to the fastening means 10.

It will be noted that the upper edge of the walls 31, 24, 33, and 34 are cut on a curvature concentric with the axis 16 so that when the boxes are swung forwardly the upper edges of these walls will clear the flange 13, but it will be understood that the sectional boxes cannot be removed without adjusting downwardly the stop bar 38 to permit the rear wall 18 to clear the flange 13, at which time the boxes can be lifted off the open hinge 16. When the sectional boxes are being installed the usual molding strips 43, 44 and 45 are secured in place.

In use it will be understood that where the invention is used for sectional letter boxes, the postman will be provided with a master key for the master lock 35, and upon releasing the lock bolt 37 he will swing the entire section of boxes forwardly upon the hinge 16 as shown in Fig. 4. The top of each box 17 and 17^a is open so that when the section of boxes is swung forwardly each box

will be open for access the entire depth of the box. The mail will be inserted by the postman through the top of each box 17 or 17^a after which the entire section will be 5 swung back and the lock bolt 37 shifted into locked position as shown in Figs. 1 and 2.

By means of the apertures 46, the owner of a box may ascertain whether there is 10 any mail deposited in his box, and by unlocking the door 25 or 25^a may obtain such mail independently of any of the other boxes in the section. Each door 25 and 25^a may be provided with a slot 47 for the insertion 15 of telegrams, business cards, and so forth.

It is to be understood that by describing in detail herein any particular form, structure or arrangement, it is not intended to limit the invention beyond the terms of the 20 several claims or the requirements of the prior art.

Having thus explained the nature of my said invention and described a way of constructing and using the same, although without attempting to set forth all of the forms in which it may be made, or all of the modes 25 of its use, I claim:

1. The combination of a plurality of boxes pivotally supported for swinging movement 30 as a unit, a door for each box, means for locking and unlocking each door, master controlling means for locking and unlocking said boxes to permit the same to swing as a unit, and means for limiting the swinging 35 movement thereof, said last means being adjustable to permit said boxes to be detached as a unit from the pivotal support thereof.

2. The combination of a housing member, a plurality of boxes located therein and 40 hinged supported at the front lower edge thereof, said boxes having openings at the top to permit ingress thereto, a door for each box, means for locking and unlocking each door, said housing member having a closure 45 for said openings, and a master lock for locking and unlocking all of said boxes to permit the same to be swung relatively to said closure, said boxes having stop means coacting with said closure for limiting the 50 swinging movement thereof and releasable to permit the boxes to be assembled or removed.

3. The combination of a plurality of boxes, means for independently opening each of said boxes, means for locking and 55 unlocking all of said boxes, means for hinging said boxes for swinging movement and constructed to permit said boxes to be bodily removed at predetermined times, and stop means for limiting the swinging movement 60 of said boxes and adjustable to permit the removal thereof.

4. The combination of a plurality of connected boxes having openings at the top, each box having a door provided with an 65 individual lock therefor, a master lock for

the connected boxes, means for supporting the boxes to permit movement thereof and means for detachably holding the boxes in predetermined position relative to said supporting means and inaccessible from the outside of said boxes. 70

5. The combination of a support, a plurality of boxes removably located therein, and having openings at the top, a door for each box, means for locking and unlocking 75 each door, a master lock for locking and unlocking all of said boxes to permit the same to be shifted relative to said support, and means adapted to be adjusted for permitting the removal or assembling of said 80 boxes and inaccessible for adjustment through a single box.

6. The combination of a plurality of receptacles having openings at the top, a door for each receptacle and having an individual 85 lock, a support, means for movably mounting said receptacles on said support, said means being releasable to permit removal and assembling of the receptacles, and an adjustable stop means for limiting the movement of said receptacles into open position, said stop means having a releasable connection in each receptacle for controlling the adjustment thereof, thereby to permit 90 assembling and removal of the receptacles. 95

7. The combination of a stationary support and a plurality of connected boxes having cooperating releasable hinge members adapted to be connected to permit the boxes to be swung into assembled position with respect to said support, releasable stop means carried at the back of said boxes for preventing said boxes from swinging beyond a predetermined point, a master lock for locking the boxes in normal closed position, and said hinge members having cooperating means effective to prevent disconnection thereof when the boxes are in normal open and closed positions. 100 105

8. The combination of a stationary support, a plurality of connected boxes having openings at the top, said support and boxes having cooperating releasable hinge members, means for locking said boxes in closed position relative to the support, means for preventing the boxes from swinging beyond a predetermined point, and means for controlling said last means to permit assembling and removal of the boxes with respect to said support. 110 115

9. The combination of a plurality of connected boxes having openings at the top, each box having a door and an individual lock therefor, a master lock for said boxes, a support, means for detachably hinging said 120 boxes to the support, and means having a detachable connection in each box for permitting detachment of said boxes.

10. The combination of a plurality of connected compartments, each compartment hav- 130

1
ing a door provided with a lock, a master lock for the connected compartments, releasable hinge means for swingingly supporting said compartments, stop means for limiting the swinging movement of the compartments and adjustable to permit the compartments to be swung into position to release said hinge means.

11. The combination of a plurality of connected boxes having enclosing back and side walls and open at the top, a door for each box and having a lock, a master lock for the boxes, a stop member extending along the outside of the back wall of the boxes, releasable hinge means for permitting swinging movement of the boxes, and means for vertically adjusting said stop member to restrict the swinging movement of the boxes in one position and in another position to permit them to be swung into position to release said hinge means.

12. The combination of a series of connected boxes pivotally mounted at the lower front edge thereof and each having an opening at the top, a door for each box having an individual lock, a master lock for the boxes, shiftable stop means carried by said boxes for limiting the swinging movement thereof, and an adjusting screw within each box for adjusting said stop means into position to permit the boxes to be removed.

13. The combination of a plurality of boxes, each having a common back wall and bottom wall, means for independently opening each of said boxes, releasable means connected to said bottom wall for hingedly supporting all of said boxes, and vertically adjustable stop means connected to the back wall of the boxes and adjustable to permit the boxes to be swung into position to release said hinged means.

14. The combination of a plurality of connected boxes comprising enclosing back and side walls provided with openings at the top, a door at the front of each box and having an individual lock, a master lock for the connected boxes, means for supporting said boxes to permit shiftable movement thereof, releasable hinge means for detachably holding the boxes against removal when swung into normal open and closed positions, and means within a plurality of boxes and inaccessible from the outside thereof for permitting said boxes to be bodily removed.

15. The combination of a casing, a plurality of connected mail boxes swingingly supported therein, each box having an opening at its top, a master lock for the connected boxes, an individual door for each box, an individual lock for each door, securing means for securing the casing in position in a wall opening and inaccessible either when the boxes are open or closed and accessible only upon the removal of the boxes from their supporting means, and means for per-

mitting the removal of the boxes from their supporting means when in their open position and inaccessible when the boxes are closed.

16. The combination of a casing, means for securing the casing in position in a wall opening, a plurality of connected mail boxes shiftable supported within said casing and each having an opening at its top, a master lock for the connected boxes, each box having a door provided with an individual lock therefor, said casing securing means being inaccessible for the release of the casing when the connected boxes are in assembled position in the casing either in the closed or open position of the boxes, and adjustable means for permitting the attachment of the boxes subsequent to the attachment of the casing in the wall opening and accessible only thru a plurality of boxes when the boxes are open.

17. A device for holding mail comprising a casing adapted to be secured in a wall by fastenings inserted from inside the casing, a receptacle mounted in said casing and having a plurality of mail receiving compartments therein, said casing having an opening in the front thereof to receive said receptacle, hinge means enclosed in said device and connecting the front part of said receptacle with said casing at the lower side of said opening and comprising separable members permitting the mounting of the receptacle in its normal position in the casing after the casing has been secured in a wall, and means for locking said receptacle in its closed position.

18. A device for holding mail comprising a casing adapted to be secured in a wall by fastenings inserted from inside the casing, said casing having an opening in the front thereof, a receptacle mounted in said casing with the front thereof normally positioned in said opening, said receptacle comprising a plurality of mail receiving compartments, hinge means connecting the front part of said receptacle with the casing at the lower side of said opening and permitting said receptacle to swing into either an open or closed position, said hinge means comprising cooperating members carried, respectively, by said receptacle and casing, said members being enclosed in said device and being readily separable to permit the mounting of the receptacle in the casing or its removal therefrom after the casing has been secured in a wall, and a lock for securing said receptacle in its closed position.

19. The combination of a casing, a plurality of connected mail boxes pivotally mounted in the casing, securing means for the casing inaccessible either when the boxes are closed or in mail receiving position and accessible only upon the withdrawal of the boxes from the casing and manually operable means for permitting the withdrawal of

the boxes from the casing when in their mail receiving position and inaccessible when the boxes are closed.

20. The combination of supporting means 5 adapted to be secured in a wall opening, a plurality of connected mail boxes pivotally mounted in the supporting means, securing means for the supporting means inaccessible either when the mail boxes are closed or in 10 mail-receiving position and accessible only upon the shifting of the boxes forward beyond their mail-receiving position, and means for permitting the shifting of the boxes forward beyond their mail-receiving 15 position and inaccessible when the boxes are closed.

21. A device for holding mail comprising a casing adapted to be secured in a wall by fastenings inserted from inside the casing, 20 said casing having an opening in the front thereof, a receptacle mounted in said casing and comprising a plurality of boxes rigidly secured together side by side with their upper ends open, the front portion of said receptacle normally being positioned in said opening, hinge means connecting the front part of said receptacle with the lower edge of said opening and permitting the upper end of said receptacle to swing outwardly 25 through said opening into an open position, said hinge means comprising rigid separable members enclosed in said device and permitting the mounting of the receptacle in said casing after the casing has been secured in 30 a wall, and a lock for securing said receptacle in its closed position.

22. A device for holding mail comprising a casing, a plurality of connected mail boxes pivotally mounted in the casing and removable 40 from or replaceable in the casing while the casing is in its operative position, securing means for the casing inaccessible either when the boxes are closed or in mail-receiving position and accessible only upon the 45 withdrawal of the boxes from the casing, and means for locking said boxes in their closed position.

23. A device for holding mail comprising a casing adapted to be secured in a wall by 50 fastenings inserted from inside the casing,

a receptacle mounted in said casing and adapted to hold mail, means for supporting said receptacle for swinging movement into an open or closed position, said fastenings being inaccessible when said receptacle is in either its closed or open position, and said supporting means permitting an additional movement of said receptacle to afford free access to said fastenings, and means for locking said receptacle in its closed position. 60

24. A device for holding mail comprising a casing adapted to be secured in a wall by fastenings inserted from inside the casing, a receptacle mounted in said casing and having a plurality of mail-receiving compartments therein, said casing having an opening in the front thereof to receive said receptacle, members enclosed within said device for supporting said receptacle for tilting movement through said opening into an open or closed position, said supporting members for the receptacle being arranged to permit the mounting of the receptacle in its normal position in the casing after the casing has been secured in a wall, and a lock for securing said receptacle in its closed position and preventing the removal of said receptacle from said casing. 70

25. A device for holding mail comprising a casing open at the front and adapted to be secured in a wall by fastenings inserted from inside the casing, a member movably mounted in said casing and provided with compartments for the reception of mail, parts enclosed within said device for supporting said movable member for tilting movement into an open or closed position with relation to the opening in the casing, said supporting parts and said movable member being separable to give free access to the interior of the casing, a lock for securing said movable member in closed position and preventing the removal thereof from said casing, independent doors in said member, and independent locks for said doors to permit each of said doors to be opened independently of the other. 80

Signed at Brooklyn, New York, this 13th day of August, 1924.

HENRY WILHELM.
